(57) **CLAIM**

The ornamental design for an electronic board, as shown and described.

DESCRIPTION

FIG. 1 is a front perspective view of an electronic board, showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a rear perspective view thereof;
FIG. 9 is an enlarged view of the portion, '9' in FIG. 1;
FIG. 10 is an enlarged view of the portion, '10' in FIG. 5;
FIG. 11 is an enlarged view of the portion, '11' in FIG. 8;
FIG. 12 is another front perspective thereof of the electronic board of FIGS. 1-11, shown in an alternate configuration in which the terminal tray is removed;
FIG. 13 is a rear perspective view of FIG. 12; and,
FIG. 14 is an enlarged view of the portion, '14' in FIG. 13. The even dash broken lines represent portions of the electronic board and form no part of the claimed design.
